UNITED STATES PATENT OFFICE.

THOMAS ELLIOTT, OF CINCINNATI, OHIO, ASSIGNOR TO THE CINCINNATI CAR COMPANY, OF WINTON PLACE, OHIO, A CORPORATION OF OHIO.

MAT FOR CAR FLOORS.

Application filed April 14, 1926. Serial No. 101,979.

This invention relates to improvements in mats or protectors for use in connection with cars.

With the protecting strips now generally employed on car floors the water and dirt carried into the car falling between the strips on to the car floor proper cannot all be removed by sweeping or otherwise and as a result causes the strips to rot necessitating their replacement from time to time. Besides, the water seeps under the strips between the connections of the car floor boards and also causes the floor proper to deteriorate. In addition to impairing the protecting strips and the floor proper the general appearance of the floor is made unattractive due to the difficulty in removing all the dirt which gathers between the strips.

It is the object of the present invention to overcome these objectionable features and to that end I provide a floor mat made up of a plurality of wooden members or strips connected by metallic gutters which will keep any water or dirt carried into the car from getting under the mat thereby preserving the mat and the floor proper of the car and at the same time providing a mat of an ornamental character due to the metallic gutters which are kept bright by sweeping.

It is a further object of the invention to provide means for permitting the water and dirt or other accumulations to be swept from one mat to another when the strips and gutters of the one mat are laid at right angles to the strips and gutters of another mat.

It is a further object of the invention to provide the gutters of such width that the narrow heels of women's shoes may not enter them, thereby preventing the liability of accidents.

In the accompanying drawings:—

Figure 1 is a plan view of a part of a car floor equipped with my improved mats.

Figure 2 is a perspective view of a mat secured to a section of floor.

Figure 3 is a sectional view taken on the line 3—3 of Figure 1 showing the inclined joining surfaces of two mats laid at right angles to one another.

Referring to Figure 1 the numeral 1 designates the floor proper of a passenger section of a car and 2 the floor proper of the platform section where the motorman is stationed and the passengers enter or leave the

car. In the passenger section the longitudinally extended seats are indicated at 3 and the crosswise seats at 4. In the platform section the usual controller is shown at 5 and the fare box at 6, both adjacent a seat 7 for the motorman. The doors at the front and rear of the car are controlled by the levers 8 and 9 respectively. The motorman's compartment is usually separated from the passageway for the entrance and exit of the passengers by railings 10 and 11.

It is customary to provide the portions of the floor between the seats on either side of the passenger section of the car with a series of wooden strips spaced apart to form gutters for the water which is carried into the cars, but it has been found that this construction is open to numerous objections. In the first place, the water and dirt carried into the car falling onto the floor proper between the strips work in under the protecting strips and rot them. Again, the water seeps down between the floor board connections and causes deterioration of the floor proper. This deterioration is often accentuated by salt which is carried into the car during times when the streets are icy. A further objection is that it is difficult to keep these spaces between the strips clean, thereby presenting an unsightly appearance.

The present invention overcomes all these objections and consists in forming a mat consisting of a series of wooden strips 12 joined together by metallic gutters 13, preferably made of brass. The wooden members are spaced parallel to one another and at a distance apart slightly less than the width of the upper outer edges of the gutters so that the latter will bite into the wood and form a water-tight joint, as shown at 14. In this way any water or dirt that is carried into the car by the passengers, or otherwise, is received by the gutters, from which they may readily be removed, as by sweeping, which serves to keep the metal bright, thereby providing a floor mat of an attractive appearance in addition to its practical advantages. It will also be noted that I prefer to form the metallic gutters of such size that narrow heels of women's shoes may not enter them.

In cars where the floors of the platform are on a level with the floor of the seating section it is desirable to provide mats for

the platforms positioned so that the wooden strips and gutters thereof will be at right angles to the wooden strips and gutters of a mat in the seating section.

5 In order to provide a connection between the two mats which will permit the water and dirt to be swept from the gutters in the mat in the seating section on to the mat on the platform, I cut away the end of the seating section mat from the top of the gutters downwardly and inwardly at an oblique angle to form an extension 15 having an inclined surface 16, while the outside wooden strip of the platform mat which is placed 10 adjacent the seating section mat is cut away from the lower edge upwardly at an oblique angle to form an extension 17 having an inclined surface 18 corresponding to the surface 16. This will permit the extension 15 15 of the seating section mat to overlap the extension 17 of the platform mat and form a water-tight joint therebetween.

The mats may be secured to the floor proper in any suitable manner, screws 19 being 25 shown in the gutters 13 in Figures 2 and 3.

From the foregoing description it will be apparent that I have provided a mat for car floors which is highly efficient, keeping the feet of the passengers out of any water that 30 accumulates on the floor and at the same time preserving the floor of the car and presenting an attractive appearance due to the fact that the metallic gutters may be kept clean and bright by sweeping.

35 It will be understood that I desire to comprehend within my invention such modifications as may be necessary to adapt it to varying conditions and uses.

Having thus fully described my invention 40 what I claim as new and desire to secure by Letters Patent, is:—

1. In a mat for a car floor, a plurality of strips and gutters interposed between said strips, the connection between said strips and gutters being water-tight.

45 2. In a mat for a car floor, a plurality of wooden strips and metallic gutters interposed between said strips, the connection between said strips and gutters being water-tight.

50 3. In a mat for a car floor, a plurality of strips, gutters interposed between said strips, the connection between said strips and gutters being water-tight and the ends of said strips and gutters being cut away at an oblique angle.

55 4. In a mat for a car floor, a plurality of wooden strips, metallic gutters interposed between said strips, the connection between 60 said strips and gutters being water-tight

and the ends of said strips and gutters being cut away at an oblique angle.

5 In a mat for a car floor, a plurality of strips, gutters interposed between said strips, a second plurality of like strips and gutters 65 extending at right angles to said first mentioned strips and gutters, the connections between said strips and gutters being water-tight, and means for positioning the first mentioned strips and gutters relatively to 70 the second mentioned strips and gutters to form a water-tight joint, whereby any water or dirt may be swept from the first mentioned strips and gutters on to the second mentioned strips and gutters. 75

6 In a mat for a car floor, a plurality of wooden strips, metallic gutters interposed between said strips, a second plurality of like wooden strips and gutters extending at right angles to said first mentioned strips and gutters, the connections between said strips and gutters being water-tight, and means for positioning the first mentioned strips and gutters relatively to the second mentioned strips and gutters to form a water-tight joint, whereby any water or dirt 80 may be swept from the first mentioned strips and gutters on to the second mentioned strips and gutters. 85

7. In a mat for a car floor, a plurality of strips, gutters interposed between said strips, a second plurality of like strips and gutters extending at right angles to said first mentioned strips and gutters, the connections between said strips and gutters being water-tight, the ends of the first mentioned strips and gutters being cut away at an oblique angle and the outside strip of the second mentioned series of strips and gutters being cut away at a corresponding angle, the two angular surfaces being adapted to be positioned relatively to one another to form a water-tight joint. 95

8. In a mat for a car floor, a plurality of wooden strips, metallic gutters interposed between said strips, a second plurality of like wooden strips and gutters extending at right angles to said first mentioned strips and gutters, the connections between said strips and gutters being water-tight, the ends of the first mentioned strips and gutters being cut away at an oblique angle and the outside strip of the second mentioned series of strips and gutters being cut away at a corresponding angle, the two angular surfaces being adapted to be positioned relatively to one another to form a water-tight joint. 105

In testimony whereof, I affix my signature.
THOMAS ELLIOTT.
